UNITED STATES PATENT OFFICE

HUGH P. McMILLAN, OF BALTIMORE, MARYLAND, ASSIGNOR TO SAMUEL M. DELL & CO., INC., OF BALTIMORE, MARYLAND

BRUSH HANDLE

Application filed July 11, 1929. Serial No. 377,481.

The invention relates to an improvement in the handle of brushes, particularly paint and varnish brushes of all sizes and shapes. It is a common experience in painting or 5 varnishing that the hand of the painter quickly becomes sore or calloused between the thumb and forefinger. It is also a common experience that the fingers quickly tire and become cramped from the effort to maintain 10 the brush in proper position. The purpose of the present invention, therefore, is to provide a simple and inexpensive construction which overcomes the above-mentioned and other objectionable features, and permits the 15 hand and fingers to remain in a natural position while grasping the brush handle, and at the same time permits a firmer grip on the brush handle, and without causing the hand to become sore or calloused.

20 The invention will be clearly understood from the following description, when taken in connection with the accompanying drawing, in which

Figure 1 is a plan view of the improved 25 paint or varnish brush, the ferrule and bristles being shown merely in outline.

Figure 2 is a perspective view of the improved brush grasped in the hand; and

Figure 3 is an end view of the brush, a 30 hand grasping the handle being illustrated in outline.

Referring to the drawing more in detail, numeral 1 indicates the head of the brush, to which the ferrule 2 and bristles 3 are attached. The handle, in the improved form, 35 as illustrated in Figs. 1, 2 and 3, is indicated by numeral 4, and it will be noted that this handle is turned through an angle of about 30 degrees with respect to the head 1. In 40 the conventional paint or varnish brush handle, the handle and the head are in the same plane.

While the drawings of the improved handle show it positioned at about 30 degrees 45 with respect to the head, it will, of course, be understood that this angle may be varied as desired. The angular positioning of the handle with respect to the brush, in accordance with this invention, accomplishes several very desirable results. In the first place,

the handle is thereby caused to just comfortably fit and fill the space between the thumb and forefinger. This prevents the brush handle from continually rubbing against the skin and causing blisters and callouses. In 55 the second place, this angular relation of the handle, permits it to be grasped in such a manner that even though it is held very lightly, yet it will not turn in the hand. In the third place, this angular relation of the handle permits the thumb to naturally encircle the handle to such an extent that it permits pressure to be easily applied to the brush without straining or tiring the fingers or 60 thumb.

In general, this invention provides a handle construction for paint or varnish brushes, which permits the brush to be firmly held in a natural and unstrained manner, whereby 65 the handle may be held more firmly and with less effort than has heretofore been possible, and at the same time prevents the hand from becoming blistered or otherwise injured.

Having fully described the invention, what 70 I claim as new is:

A paint brush including a flat head, and a handle of a general oval shape in cross-section, the central plane of said handle being positioned at an oblique angle with respect 75 to the central plane of said head.

HUGH P. McMILLAN.
